UNITED STATES PATENT OFFICE.

EPHRAIM J. STORY, OF WASHINGTON, DISTRICT OF COLUMBIA.

FIRE-CHAMBER.

SPECIFICATION forming part of Letters Patent No. 372,774, dated November 8, 1887.

Application filed July 24, 1886. Serial No. 208,976. (No model.)

To all whom it may concern:

Be it known that I, EPHRAIM J. STORY, a citizen of the United States, residing in Washington, in the District of Columbia, have invented certain new and useful Improvements in Fire-Chambers for Fire-Places and Stoves, of which the following is a description.

The invention relates to fire-chambers or fuel-chambers for use in fire-places and in some kinds of stoves or heaters, the object being to produce a complete portable fire-chamber which shall be simple and inexpensive, strong and durable, which shall resist the action of heat, so as to be secure against every tendency to warp or to bend, which shall have large radiating-surface, and which shall have means for agitating the contents of a grate when such grate is reciprocated.

With this object in view the invention consists in various novel elements and in various novel combinations of elements in a fire-chamber, as will be hereinafter indicated in the description and claims.

In the drawings, Figure 1 is a rear perspective elevation of a fire-chamber in which my improvements are embodied. Fig. 2 is a detail perspective, partly in section, on the line xx of Fig. 3. Fig. 3 is a perspective view looking toward the interior of the right-hand portion of the chamber. Fig. 4 is a rear elevation of the central section of the fire-chamber, the intersecting radiating and strengthening ribs being shown in a slightly-modified form.

The fire-chamber A consists of a central rear section, A', and left and right hand end sections, A² and A³, each of the three sections being formed in a single piece of metal. The rear section, A', at a point somewhat below its mid-height, is provided with a rearwardly-overhanging projection, a', and it is provided also with flaring vertical end portions, a⁴ and a⁵, which have orifices o, a horizontal top plate, a⁶, and intersecting strengthening and heat-radiating ribs a⁸. The end section, A³, is composed of the two vertical portions a⁹ and a¹¹ and the connecting longitudinally horizontal overhanging portion a¹⁰, the cap or top piece, a¹², preferably curved as shown, the flaring end portion, a¹³, having orifices o', the front plate or flange, a¹⁴, and the intermediate cell-like strengthening and radiating ribs, a¹⁵.

Within the angle formed at the junction of the lower vertical portion, a⁹, with the connecting longitudinally horizontal portion a¹⁰, one or more projections or protuberances, a¹⁶, each having a perforation to receive a supporting-pin, a¹⁷, is formed with the end section or casing, A³, such projection or reinforcement serving to strengthen the parts at their point of union and to furnish a long and firm bearing for the supporting-pin, which may be provided with a shoulder to bear against the projection and with a securing-nut, a¹⁸. The end section, A², as will be readily inferred from the foregoing, is the exact counterpart of the section A³—that is, it is in all respects identical with it in construction and function of the parts, and differs only in their opposite arrangement.

The overhanging connecting portion a¹⁰ serves in the reciprocation of any grate or grates which may be applied for use in connection therewith to clear the top surface of the ends of the same, and thus prevent clogging by the collection of cinders, slag, or coals between the grate and the lower vertical end portion, a⁹. The sections A' A² A³ are secured together by means of bolts b, which extend through the orifices o and o'.

It will be understood that, unlike ordinary fire-chambers, this chamber is to be used without a lining, the burning fuel resting in direct contact with the metallic walls of the structure. The intersecting ribs, integral with the outer surface of these metallic walls, whether crossing and supporting each other at right angles, as best seen in Figs. 1 and 4, or at some other angle, serve to strengthen the plates thus subjected to intense heat against every tendency to warp or to bend and to reduce to a minimum their liability to fracture; and they also present to the contiguous air-warming chamber a very extensive heat-radiating surface, each rib extending outwardly from its vertical base a distance of preferably not less than an inch and one-half.

In the drawings the overhanging shoulder or clearing projection is represented as in two different transverse planes, which meet near the transverse center of the chamber; but it is obvious that any other desired form might be employed without affecting the operation of the parts or the principle of the invention.

In Figs. 2 and 3 of the drawings I have represented portions of a reciprocating grate substantially like that in United States patent issued to me August 3, 1886, and numbered 5 346,830, and the clearing projections herein described are well adapted to operate advantageously in connection with a grate of that character; but any right-and-left reciprocating grate, extending under these overhanging clearing projections may be employed with equal advantage in connection with them.

It will be understood that, inasmuch as my fire-chamber is composed wholly of metal and intended and adapted to be used without either 15 interior lining or exterior covering, I do not claim any construction in which either linings or coverings constitute a part of the structure.

Having thus described my invention, I claim—

- 20 1. A metallic fire-chamber which is provided with rear and end exterior integral strengthening and radiating ribs and with an interior overhanging shoulder or clearing projection, in combination with a reciprocating grate, the contents of which, when the grate is shaken, are agitated by such clearing projection.
- 25 2. A fire-chamber which has rear exterior integral horizontal and vertical strengthening and radiating ribs which overhang a lower portion of the space behind the chamber and end exterior integral horizontal and vertical ribs which overhang the ends of the ash-pit.
- 30 3. A fire-chamber which has end sections which are provided with integral intersecting strengthening and radiating ribs and which each overhang the ash-pit, and which has also a

rear section which is provided with integral intersecting strengthening and radiating ribs and which overhangs the space directly behind the ash-pit. 40

4. The combination, with the rear section, A', having plain inner surface and exterior overhanging projection a', of the end sections, A² and A³, each having vertical portions a⁹ a¹¹ 45 in different planes, which are united by a longitudinally horizontal connecting portion, a¹⁰, which overhangs the ash-pit, substantially as and for the purposes set forth.

5. In a fire-chamber, an end section which has an inwardly-extending longitudinally horizontal grate-clearing projection and a perforated enlargement or re-enforcement beneath and integral with such grate-clearing projection. 50

6. The combination, with the end sections, 55 of the grate supporting pin beneath the overhanging projection thereof, extending through each section and projecting into the ash-pit, as shown and described.

7. The herein-described fire-chamber, consisting of central rear section, A', having intersecting strengthening and radiating ribs and rearwardly-overhanging projection a', and the end sections, A² and A³, each having intersecting strengthening and radiating ribs 65 and an inwardly-extending overhanging projection, each of these sections, with its ribs and projection, being formed in a single piece, and the entire chamber being adapted to be used without lining or covering, as set forth. 70
